UNITED STATES PATENT OFFICE.

EUGENE H. BALLOU, OF PAWTUCKET, RHODE ISLAND, ASSIGNOR TO DRAPER CORPORATION, OF HOPEDALE, MASSACHUSETTS, A CORPORATION OF MAINE.

AUTOMATIC WEFT-REPLENISHING LOOM.

1,272,601.

Specification of Letters Patent.

Patented July 16, 1918.

Application filed August 6, 1917. Serial No. 184,704.

To all whom it may concern:

Be it known that I, EUGENE H. BALLOU, of Pawtucket, in the county of Providence and State of Rhode Island, have invented 5 certain new and useful Improvements in Automatic Weft-Replenishing Looms, of which the following is a specification.

In Letters Patent of the United States, Number 1,244,827, October 30, 1917, there is 10 described an automatic weft replenishing loom in which the shuttle box at the replenishing side of the loom is yieldably connected with the lay, and, when a change of weft is called, the shuttle box at the re- 15 plenishing side of the loom is stopped when about half way forward, while the lay continues its regular forward movement, the transfer of a fresh weft carrier into the shuttle taking place while the shuttle box 20 containing the shuttle is standing still.

The object of the present improvements is to prevent the action of the replenishing mechanism in the event that the shuttle is not properly positioned in the shuttle box, 25 thereby avoiding damage either to the shuttle or to the weft carriers.

The present improvement is illustrated in the accompanying drawings, wherein—

Figure 1, is a front view of the replenishing side of the loom. Fig. 2 is a side view 30 of the same. Fig. 3, is a horizontal section in the plane indicated by the line 3—3 in Fig. 2. Fig. 4, is a longitudinal section in the plane indicated by the line 4—4 in Fig. 35 1. Fig. 5, is a horizontal section in the plane indicated by the line 5—5 in Fig. 2. Figs. 6 to 10, are detail views.

Figs. 1 and 2, illustrate the parts in the position they occupy just as the transerrer 40 has acted to insert a fresh weft carrier in the shuttle.

Reference numerals are used to indicate parts which correspond with those described in the aforesaid Patent No. 1,244,827, and 45 reference letters are used to describe the new parts.

The magazine 1, with contained weft carriers 2, is of the rotary type used in the Northrop loom, as illustrated in United 50 State Letters Patent of E. S. Stimpson, No. 664,790, December 25, 1900. Coöoperating with the magazine is the usual transerrer 3, pivoted at 4. The shuttle box 5, at the replenishing side of the loom is carried by 55 a frame 6, which is pivotally mounted at

its lower end independently of the lay with its axis in line with the axis of the lay. As shown in Fig. 1, the shuttle box frame 6, has an inner bearing 7, turning on the lay rock shaft 8, and an outer journal 9, turning in 60 an independent bearing 10. The lay 11, has a lateral extension 12, extending in front of the shuttle box. The shuttle box frame 6, carries a horizontal rock shaft 13, which in turn carries a projection 14, thereon, 65 which is connected by a strap 15, with a spring 16, fastened at its lower end to the shuttle box frame 6. The shuttle box has fast on it at its opposite ends drums 17 each of which is connected by a strap 18, to 70 a bracket 19, fastened to the lay extension 12. The drawings show only one of the drums 17, and straps 18, the duplication being illustrated in said Patent No. 1,244,827. During the ordinary running of the loom 75 the spring 16, and the described connections 13, 14, 15, 17, 18 and 19, maintain the shuttle box and the lay together so that they move in unison. When, however, a change of weft is called, the shuttle box and its frame 80 are stopped when about half way forward while the lay continues its forward movement, this being permitted by the yielding spring 16. When the lay begins to retreat the spring 16, takes up the lost motion between the shuttle box and the lay extension 12, and thereafter the shuttle box and lay move together. This stoppage of the shuttle box is under the control of detecting mechanism which detects the need for weft re- 85 plenishment. The detecting mechanism may be of any of the well known types now in use. The detector may be a weft fork which detects the absence of weft and sets the weft replenishment instrumentalities into action, 90 as in United States Letters Patent of Northrop No. 529,940, November 27, 1894, or it may be a feeler which detects approaching exhaustion of weft, as in United States Letters Patent of Northrop No. 600,016, 100 March 1, 1898. Whichever detector is employed, the starting shaft 20, is rocked and an arm 21, thereon, is lifted. This arm 21, is connected by a link 22, with a crank arm 23, fast on the forward end of a rock shaft 24. 105 Near its rear end this rock shaft has fast on it a shifter fork 25, which engages a peripheral groove 26, in a sleeve 27, which is splined on the cam shaft 28, of the loom. The lifting of link 22, swings the shifter 110

fork 25, so as to move the sleeve 27, outwardly thereby bringing a normally idle cam 29, thereon beneath the rear end of a replenishing lever 30, pivoted at 31. As the cam 29, rotates with the cam shaft 28, it encounters the rear end of the replenishing lever 30, and lifts the same against the tension of a spring 32. This spring 32, normally maintains the rear end of the lever 30, in its lowermost position, and in such position a stop 33, on a rod 34, which is pivotally connected with the lever 30, encounters the front end 35, of a detent 36, pivoted at 37, thereby maintaining a shoulder 38, of the detent above and out of reach of an abutment 39, carried by a sliding arm 40, which is pivoted at 41, to the shuttle box frame 6. When the rear end of replenishing lever 30 is raised the stop 33, is lifted to the position shown in Fig. 2, and the heavier rear end of the detent 36, drops so as to bring its shoulder 38, into the path of the abutment 39. Then, as the lay and shuttle box move forward, the abutment 39, encounters the shoulder 38, of the detent and prevents any further forward movement of the shuttle box while the lay continues to move forwardly being thus permitted to move by the yielding of the spring 16. In this manner the shuttle box at the replenishing side of the loom is stopped in proper position to receive the lowermost weft carrier in the magazine.

At its forward end the replenishing lever 30, is adjustably connected with an arm 42, which at its upper end has a lost motion connection with a link 43, pivotally connected with the transferrer 3. This lost motion connection permits the lever 30, to move under the influence of the cam 29, sufficiently far to permit the stoppage of the shuttle box before any motion is transmitted to the transferrer. Thereafter, the continuance of the movement of the replenishing lever 30, results in the swing of the transferrer 3, so as to transfer the lowermost spare weft carrier in the magazine into the shuttle then occupying the stationary shuttle box. Fig. 2, shows the replenishing lever 30, moved to its extreme position by the cam 29, and the transferrer 3, in its lowermost position. Accordingly, the transfer of the fresh weft carrier through the shuttle takes place when the shuttle is standing still. After the transfer is effected the cam 29, passes the replenishing lever 30, and said lever is restored to its normal lowermost position by the spring 32, thus lifting the transferrer to its normal uplifted position and also lifting the rear end of the detent 36, so as to get its shoulder 38, out of the path of the abutment 39, on the sliding arm 40. As the lay retreats, the spring 16, and its connections with the lay extension 12, again unite the shuttle box to the lay so that thereafter they

move in unison. After the transfer is completed, a spring 44, restores the rock shaft 24, to its idle position with the cam 29, out of reach of the replenishing lever 30. All of the parts as thus far described are similar to corresponding parts in the aforesaid Patent No. 1,244,827, to which reference is made for a full description of the construction and mode of operation. 70

It is important that the shuttle should be 75 properly positioned in the shuttle box at the replenishing side of the loom at the time the transfer is made. Otherwise, breakage may occur. The improvements constituting the present invention reside in the mechanism 80 which prevents the disconnection of the shuttle box from the lay and the action of the transferrer unless the shuttle is properly positioned. When the shuttle is in proper position in the shuttle box 5, it is in 85 contact with the picker 45, carried by the picker stick 46. When the shuttle is in proper position the picker stick 46, is in contact with the upper end of a lever A, which is pivoted at B, to the shuttle box 90 frame 6. The lower end of the lever A, has pivotally connected with it a link C, which extends inwardly in a nearly horizontal direction, as shown in Fig. 1, and at its inner end it is bent to form a stud D. The link C, and its stud D, are upheld and guided by a guide E, which is fast on the rock shaft 24. When the shuttle is correctly positioned the stud D, occupies the inner position shown in Fig. 8, and in full lines in 100 Fig. 3, and the rock shaft 24, then maintains the cam 29, in operative relation with the replenishing lever 30. There is sufficient lost motion between stud D, and guide E, and between link C, and lever A, to permit 105 the rocking of the shaft 24, and to compensate for the swing of the shuttle box frame 6.

In the event, however, that the shuttle is not properly positioned in the shuttle box 5, the lever A, will be moved at its upper end 110 inwardly against a fixed stop F, on the shuttle box frame 6, by a spring G, so that the stud D, will then occupy the outer position shown in Fig. 10, and in dotted lines in Fig. 3. When the stud D, is in this outer position 115 it is in the path of a controller consisting of vibrating lever H, pivoted at I. The rear end of this controller co-acts with a controlling cam J, on the cam shaft 28, with which it is maintained in operative relation by the 120 spring 32. The cam J, lifts, and the spring 32, depresses; the forward end of the controller H. The forward end of the controller swings up and down freely when the stud D, is out of its path. When the controlling cam J, acts upon the rear end of the controller H, and the forward end of the controller H, is below the path of the stud D, said stud is beneath the forward end of said controller. 125 130

The timing of the cam J, is such that, as shown in Fig. 6, it is about to act on the controller H, just after the shuttle has entered the box at the replenishing side of the 5 loom. If a change of weft has been called, the shaft 24, at this time has been rocked so as to lower the guide E, and the stud D, so that the latter is just above the controller H, and the replenishing cam 29, is ready to 10 act on the replenishing lever 30. If at this stage, the shuttle is properly positioned, the stud D, is in its innermost position, out of the way of the controller H, so that when the controlling cam J, acts, the forward end 15 of said controller H, passes upwardly past the stud D, to the position shown in Figs. 7 and 8, and the replenishment takes place.

In the event, however, that the shuttle is 20 improperly boxed at the critical period, the stud D, occupies the outer position (Fig. 10) and is in the path of the controller H. Hence when said lever is swung by cam J, it encounters the stud D, thereby moving the stud and guide E, to the position shown in 25 Figs. 9 and 10. This movement rocks the shaft 24, so as to move the sleeve 27, inwardly, thereby moving the replenishing cam 29, out of reach of the replenishing lever 30, so that the transfer is not made.

To permit the rocking of the shaft 24, by 30 the controller H, the link 22, is made yieldingly extensible as shown in Fig. 5. The link 22, is made of two rods K and L. A sleeve M, is secured to rod L, and has a guide 35 N, in which rod K, slides. The rod K, is surrounded by a spring O, which bears at its top against the guide N, and at its bottom against a collar P, on the rod K. Hence, when controller H, rocks the shaft 24, 40 the spring O, yields thus permitting the rod L, to move down while rod K, stands still. The spring O, is sufficiently stiff to insure the shaft 24, being rocked when the arm 21, is lifted.

When the loom is normally running, the 45 guide E, occupies the position shown in Fig. 1, with the stud D, above reach of the controller H, so that the stud is encountered by the lever only in case the shuttle is not properly positioned when a change of weft is 50 called by the detector and the starting shaft 20, is rocked.

I claim—

1. An automatic weft replenishing loom 55 wherein when replenishment is effected the shuttle box stands still while the lay continues to move forward having, in combination, a replenishing lever which by its movement causes the dwell of the shuttle box and 60 the supply of weft thereto; a normally ineffective rotary and sliding replenishing cam coöperating with said replenishing lever when replenishment is demanded; a rock-shaft connected with said cam and acting to 65 slide said replenishing cam into and out of

reach of the replenishing lever; a starting shaft which is rocked when replenishment is required; a yieldingly extensible connection between said shafts; a guide fast on said rock shaft; a stud movable on said guide; a 70 rotary controlling cam; a controller moved by said controlling cam and adapted to encounter said stud so as to move said replenishing cam to ineffective position in the event that the shuttle is not properly boxed 75 at the replenishing side of the loom; the picker at the replenishing side of the loom; a spring actuated lever which is swung in opposition to its spring when the picker is forced outwardly by the shuttle; and connections between said lever and said stud whereby said stud is in the path of the controller when the shuttle is not properly boxed and is out of such path when the shuttle is correctly boxed. 80

2. An automatic weft replenishing loom wherein when replenishment is effected the shuttle box stands still while the lay continues to move forward having, in combination, a replenishing lever which by its movement causes the dwell of the shuttle box and the supply of weft thereto; a normally ineffective replenishing cam coöperating with said replenishing lever when replenishment is demanded; a rock-shaft connected with 90 said cam and acting to move said cam into and out of reach of the replenishing lever, said shaft being rocked when replenishment is required; a stud movable on said rock shaft; a rotary controlling cam; a controller 95 moved by said controlling cam and adapted to encounter said stud so as to move said replenishing cam to ineffective position in the event that the shuttle is not properly boxed at the replenishing side of the loom; the 100 picker at the replenishing side of the loom; and connections between said picker and said stud whereby said stud is in the path of the controller when the shuttle is not properly boxed and is out of such path when the shuttle is correctly boxed. 105

3. An automatic weft replenishing loom wherein when replenishment is effected the shuttle box stands still while the lay continues to move forward having, in combination, a replenishing lever which by its movement causes the dwell of the shuttle box and the supply of weft thereto; a normally ineffective replenishing cam adapted to coöperate with said replenishing lever; weft-governed means acting to move said cam to effective position when replenishment is demanded; a rotary controlling cam; a controller moved by said controlling cam and acting to move said replenishing cam to ineffective position in the event that the shuttle is not properly boxed at the replenishing side of the loom; the picker at the replenishing side of the loom; and connections between said picker and said controller where- 115 120 125 130

4
by said controller acts when the shuttle is not properly boxed and is idle when the shuttle is correctly boxed.

5 4. An automatic weft replenishing loom wherein when replenishment is effected the shuttle box stands still while the lay continues to move forward having, in combination, a replenishing lever which by its movement causes the dwell of the shuttle box and 10 the supply of weft thereto; a replenishing cam coöperating with said replenishing lever when replenishment is demanded; a controller acting to move said cam to ineffective position in the event that the shuttle is not 15 properly boxed at the replenishing side of the loom; and means governed by the position of the shuttle in the box at the replenishing side of the loom to render said controller active when the shuttle is not prop-

erly boxed and to render said controller idle 20 when the shuttle is correctly boxed.

5 5. An automatic weft replenishing loom wherein when replenishment is effected the shuttle box stands still while the lay continues to move forward having, in combination, replenishing means which causes the dwell of the shuttle box and the supply of weft thereto; and a controller for said replenishing means which is governed by the position of the shuttle in the box at the replenishing side of the loom, so that the shuttle box stops and replenishment is effected only when the shuttle is correctly boxed. 25 30

In witness whereof, I have hereunto 35 signed my name.

EUGENE H. BALLOU.
